UNITED STATES PATENT OFFICE

110,113

DESIGN FOR A COMBINED MAKE-UP BOX AND MIRROR

Carroll K. Marcell, New York, N. Y.

Application February 3, 1938, Serial No. 74,842

Term of patent 3½ years

To all whom it may concern:

Be it known that I, Carroll K. Marcell, a citizen of the United States, residing at New York, in the county and State of New York, have invented a new, original, and ornamental Design for a Combined Make-Up Box and Mirror, of which the following is a specification, reference being had to the accompanying drawing, forming part thereof.

The figure is a perspective view of a combined make-up box and mirror, showing my new design, the lining indicating contrasting color appearance and the broken parallel lined rectangular frame in the center panel of the lid indicating broken ornamental lines etched on the mirror surface thereof. The rear and other side of the box are substantially plain.

I claim:

The ornamental design for a combined make-up box and mirror, as shown and described.

CARROLL K. MARCELL.
